FREQUENCY GENERATING SYSTEM

Marc André Lalande, Paris, France, assignor to
International Standard Electric Corporation,
New York, N. Y., a corporation of Delaware

Application July 25, 1947, Serial No. 763,619
In France February 15, 1946

Section 1, Public Law 690, August 8, 1946

9 Claims. (Cl. 250—36)

1

The invention relates to frequency generator systems and particularly to such systems which generate sub-harmonic frequencies of a base frequency.

An object of the invention is to provide a system for generating sub-harmonics of a base frequency wherein said sub-harmonics are exact sub-multiples of the base frequency.

Another object of the invention is to provide a system for generating exact sub-multiple harmonic frequencies of a base frequency which varies over a predetermined range of frequency.

It is often required, for example in telephone carrier systems, to provide a series of frequencies which are exact multiples of a base frequency and which are very stable. Since the base frequency of such systems must be a low frequency in order that its harmonics shall be in the desired frequency range, an oscillator of such a low frequency must be provided. Such oscillators of such low frequencies are not susceptible of great stability and a resulting instability of all the harmonics of such an oscillator results.

According to the invention the series of harmonically related frequencies is provided by a system for generating sub-harmonic frequencies of a base frequency. Thus, the base frequency oscillator may be an oscillator of higher frequency than any other frequency of the series and may be, for example, a crystal oscillator of say 100 k. c. which provides a system of harmonically related frequencies which is known to be more stable than previous systems based on an oscillator of lower frequency.

Other objects and advantages of the invention will appear in the following detailed description and claims and in the drawings, in which

Fig. 1 shows a block diagram illustrating the principles of the invention;

Fig. 2 shows the schematic diagram of a first embodiment of the invention; and

Fig. 3 shows a schematic diagram of a second embodiment of the invention.

Referring to Fig. 1, a source 1 of frequency $F=mf$ where F is called the base frequency, m is any integer, and f is a sub-harmonic frequency is shown connected to a frequency changer 2 which also is supplied with a frequency f_1 , the source of which will be mentioned later. At the output of changer 2 the product frequencies include a sub-harmonic frequency f , mentioned above which is connected to a selective amplifier 3 (or a selective filter following a conventional amplifier) which selects frequency f from the other frequencies present in the output of changer

2

2. This frequency f is fed from amplifier 3 to a harmonic generating circuit 4 which multiplies frequency f by a factor $m-1$ so that frequency $f_1=(m-1)f$. f appears at the output of harmonic generator 4. Part of this output is connected to a selective amplifier 5 and thence to changer 2 as mentioned above, the remainder of this output constituting a frequency f which is an m th degree sub-multiple of the base frequency F .

In order to determine the stability of this system, suppose that, at a given instant the frequency supplied to frequency generator 4 is $f+\Delta f$ where Δf is a deviation from the desired frequency f . Then f_1 is changed to a new value f_1' such that

$$f_1'=(m-1)(f+\Delta f)$$

Then the output frequency of frequency changer 2 will be

$$F-f_1'=f-(m-1)\Delta f$$

The deviation in frequency Δf is thus multiplied by a factor $(m-1)$ and subtracted from frequency f resulting in a very rapid correction of the originally assumed incorrect frequency $f+\Delta f$ so that the correct frequency f quickly is reestablished.

The loop comprising changer 2, amplifier 3, frequency multiplier 4, and amplifier 5 must possess a net gain to maintain sustained oscillations; this loop having no particular frequency, the various filtering of selective means can be constructed so as to have a certain band width which may attain a value equal to one-half the frequency f . It follows therefore that the only frequency controlling the system is the base frequency F . Thus the system described by the invention provides a greater frequency stability than previous systems.

The system described above presupposes existence of a steady state oscillation and it is necessary to provide an adequate device to start oscillations in the loop when it is to be used as a part of a system for carrier telephony. This can be done in several ways such as the injection of either frequency f or f_1 by means of a temporarily operative oscillator or by shock exciting one of the selective amplifiers.

Referring to Fig. 2 a circuit is shown for a particular loop which is rendered operative by temporary self-oscillation of an amplifier in the loop.

A base frequency oscillator comprising a crystal controlled oscillator utilizing a triode section of electron tube 1, and a crystal 2 ground to oscillate at the base frequency F produces stable oscillations at a frequency $F=mf$. The other elements

of electron tube 4 act as a frequency changer for the frequency F and the frequency f_1 , which is impressed on a control grid of tube 4 by means of connector 3.

The difference frequency $F-f_1=f$ is selected from the frequency changer anode of tube 4 by a selectively tuned transformer 4 connected to the frequency changer anode of tube 4 and to a control grid of electron tube 5 which is part of an amplifier for the frequency $F-f_1=f$.

The amplifier for frequency $F-f_1=f$ comprises tubes 5 and 6 which are resistance coupled in the conventional manner, and a coupling transformer 7 the primary winding of which is in the anode circuit of tube 6. The secondary winding of transformer 7 is connected to a band pass filter of conventional type designed to pass a band of frequency on either side of the frequency $f=F-f_1$. This band-pass filter is composed of the tuned secondary winding of transformer 7 and the series capacitance-inductance resonant circuit 8. This band-pass filter may be designed to pass any particular frequency band desired for particular requirements of stability.

The frequency $f=F-f_1$, after passing through the band-pass filter, is impressed on a full-wave rectifier system 9. The action of the band-pass filter and the full-wave rectifier 9 is to generate a harmonic of frequency f and this harmonic may, by adjustment of these circuit elements, be made the $(m-1)^{st}$ harmonic of f . Thus a harmonic frequency $(m-1)f$ is impressed across a transformer 10 as well as appearing at terminals 11 for use, for example, in a carrier telephone system.

The full wave rectified current output of rectifier 9 is impressed on a relay 12 operating contacts 13 in such a way that when a frequency f is rectified by rectifier 9, relay 12 opens contacts 13 disconnecting a feedback circuit including resistance 14 and capacitance 15 which is connected between the control grid of amplifier tube 5 and the anode of amplifier tube 6 to provide a feedback circuit between tubes 5 and 6, whereby these tubes shall temporarily oscillate at a frequency $f=F-f_1$ as determined by the tuned transformers 4 and 7 when contacts 13 are engaged, namely where no frequency f appears in the secondary winding of transformer 7.

Transformer 10 is connected to a band-pass filter 16 adjusted to possess a center pass frequency of $f_1=(m-1)f$. An amplifier 17 possessing a tuned output transformer 18 amplifies and further adjusts the band-pass characteristic of filter 16 and impresses the frequency f_1 on a control grid of the frequency changer portion of tube 4 by connector 3 as described above. If the magnitude of the harmonic output to transformer 10 is sufficient the amplifier stage comprising tube 17 may be omitted.

Referring to Fig 3 the circuit of a second embodiment is shown whereby the loop of Fig. 1 is rendered operative by a shock excitation of the amplifier. The complete loop is not shown. Instead an amplifier tube 19 is shown, corresponding to amplifier tube 6 of Fig. 2, connected by a transformer 20 to a band pass filter 21 the output of which is connected to a full-wave rectifier 22 and terminals 23. The band pass filter is similar to that of Fig. 2 and its bandwidth may be adjusted as therein described.

The combination of the filter 21 and rectifier 22 produces the $(m-1)^{st}$ harmonic of the frequency f and this frequency $(m-1)f$ appears at terminals 23 for use in completing the ring

circuit as in Fig. 2 and for use in, for example, a carrier telephone system.

The shock excitation is applied amplifier tube 19 as follows: As long as frequency f appears across rectifier 22, relay 24, connected to the output of the rectifier, is activated and holds its contacts 25 open allowing the amplifier to proceed normally; however, when the rectifier 22 is not supplied with a sufficient magnitude of voltage of frequency f , relay 24 is deactivated and allows its contacts 25 to close, as shown in Fig. 3. A circuit is completed from ground through contacts 25, back contacts 26 of relay 27, coil of relay 27, a resistance 28 to high tension. This circuit activates relay 27, closing its front contacts 29 which instantly cuts the voltage at point 30 to zero. This instantaneous change in voltage at point 30 causes a transient surge in amplifier tube 19 and its associated circuits whereby a frequency f is generated because the amplifier is tuned as discussed in connection with Fig. 2. When relay 27 is so activated, its back contact 26 opens causing a deactivation of relay 27. As long as contacts 25 are closed, relay 27 will thus alternately be activated and deactivated according to its natural period, continually shocking the amplifier circuit with surges of voltage until a sufficient voltage of frequency f appears across relay 24 to open contacts 25 by activating relay 24.

The rest of the operation is as in Fig. 2 where frequency $(m-1)f$ appearing at terminals 5 is fed to a band pass filter and amplifier and thence back to a frequency changer also supplied with a base frequency F whereby a frequency

$$F-(m-1)f=f$$

is supplied to the amplifier.

Although particular circuits have been utilized to illustrate the principles of the invention it is clear that other circuits could be designed according to these principles without exceeding the spirit and scope of the invention.

I claim:

1. An arrangement for obtaining multiple sub-harmonic frequency energy from a stable source of base frequency energy comprising a source of modulation frequency energy, means for modulating said base frequency energy with said modulation frequency energy to obtain a sub-harmonic frequency energy, a full wave rectifier, a sub-harmonic frequency amplifier conditioned for operating in an oscillatory or a non-oscillatory state, and means for applying said sub-harmonic frequency energy through said amplifier to said full wave rectifier, means responsive to the output of said amplifier for controlling the state of operation of said sub-harmonic frequency amplifier, said source of modulation frequency energy comprising means for deriving from said rectifier output said modulation frequency energy and means for deriving from said rectifier output the multiple sub-harmonic frequency energy.

2. An arrangement according to claim 1, wherein said means for conditioning said sub-harmonic frequency amplifier comprises means responsive to the amplitude of the output of said rectifier for stopping or starting oscillations in said amplifier.

3. An arrangement according to claim 1, wherein said means for conditioning for oscillation of said amplifier comprises means responsive to the output of said rectifier to cause said amplifier to oscillate in response to the rectified

sub-harmonic frequency energy falling below a given level and causes said amplifier to stop oscillating when said rectified sub-harmonic frequency energy rises above said given level.

4. An arrangement according to claim 1, wherein said amplifier comprises a circuit tuned to said sub-harmonic frequency and said means for conditioning said amplifier, comprises means for shock exciting said tuned circuit.

5. An arrangement according to claim 5, wherein said circuit is shock excited in response to the rectified sub-harmonic frequency energy falling below a certain level and said circuit is maintained non-oscillatory when the rectified sub-harmonic frequency energy is above said given level.

6. An arrangement according to claim 1, wherein said means for modulating said base frequency energy with said modulation frequency energy to obtain said sub-harmonic frequency energy comprises a selective circuit tuned to said sub-harmonic frequency.

7. An arrangement according to claim 1, wherein the output of said amplifier is passed through a band pass filter having a pass band 25

above or below said sub-harmonic frequency before application to said full wave rectifier.

8. An arrangement according to claim 1, wherein said means for conditioning for oscillation of said amplifier comprises a relay coupled to said rectifier output for opening or closing a portion of said amplifier circuit controlling oscillation thereof.

9. An arrangement according to claim 1, wherein said source of modulation frequency energy comprises a selective circuit tuned to said sub-harmonic frequency and coupled to the output of said rectifier.
